UNITED STATES PATENT OFFICE

SUMNER K. PRESCOTT, OF SEATTLE, WASHINGTON, ASSIGNOR TO PRESCOTT IRON WORKS, OF SEATTLE, WASHINGTON, A CORPORATION OF WASHINGTON

LUMBER TRIMMER

Application filed October 28, 1929. Serial No. 402,889.

This invention relates generally to improvements in lumber trimmers and more particularly to improvements in automatic lift mechanism for lumber trimmers of the type forming the subject matter of Patent 1,522,940, granted January 13, 1925, to J. L. Breeze for lumber trim saw.

One of the principal objects of the present invention is to provide a double mechanical lift unit for lumber trimmers which simplifies and compacts the construction and which permits the use of a variable spacing of the trimmer saws as, for example, a one or two foot spacing of the saws.

Another object of the invention is to provide a device of this character which is simple and durable in construction, reliable and effective in operation and easy and inexpensive to manufacture and install.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a plan view of a double lift unit embodying the present invention;

Figure 2 is a view thereof in end elevation;

Figure 3 is a view thereof in rear elevation, that is, looking toward the left in Figure 1;

Figure 4 is a view in longitudinal vertical section taken approximately on line 4-4 of Figure 1, and with parts shown in elevation for the sake of simplicity in illustration;

Figure 5 is a detail view in elevation of the supporting bracket employed for each lift unit and of one of the cam tracks or flanges carried thereby for controlling the operation of the lifting pawl;

Figure 6 is a fragmentary view partly in side elevation and partly in vertical section showing how the lift unit is connected up with the saw frame;

Figure 7 is a fragmentary view partly diagrammatic and partly in elevation showing

how the lifting yokes may be positioned to obtain a two foot spacing of the saws;

Figure 8 is a similar view showing how the lifting yokes are adjusted to obtain a one foot or minimum spacing of the saws;

Figure 9 is a detail perspective view of the shiftable section of one of the cam tracks or guides employed for the raising pawls; and

Figures 10 and 11 are detail views in top plan of a lowering and lifting pawl, respectively.

Referring now to Figure 6, it will be seen that the usual trimmer table designated at 1 is provided and has an upwardly inclined top 2 over which the upper run of a conveyor designated generally at 3 travels, the conveyor advancing the lumber to the trimming saws in the usual manner. Adjacent the table is a saw supporting frame work 4 on which the vertically swingable saw frames 5 are pivotally mounted in accordance with conventional practice. At the outer end of each saw frame an arbor 6 is rotatably supported and has a saw 7 fixed thereto and rotatable therewith. The arbor 6 may be rotated in the usual manner, as, for instance, in the manner shown in the Breeze patent above referred to.

As illustrated diagrammatically in Figures 7 and 8, the saws of each pair of adjacent saws are raised and lowered under the control of a double lift unit designated generally at 10. Although a single unit 10 serves two saws, each saw may be independently raised and lowered.

Referring now to Figures 1 to 4, inclusive, the numeral 11 designates the line shaft or other power actuated drive shaft. Each double lift unit has a base plate 12, supported upon and bolted to suitable framing, and carrying a sectional housing 13 provided with a bearing 14 in which the adjacent portion of the line shaft 11 is rotatably supported. Within the housing 13, a pinion 15 is keyed to the line shaft and meshes with a gear wheel 16 keyed to the central portion of a counter shaft 17 journaled in bearings 18 formed on the housing 13 on the opposite sides of the gear 16. With this construction

the shaft 17 of each double lift unit is constantly turning whenever the line shaft is driven.

At each end of the shaft 17, an arm 20 is provided, each arm 20 having a hub 21 provided with a bushing 22 and rotatably fitted on its end of the shaft 17. A washer 23 and pin 24 prevent endwise displacement of each arm 20 off of its end of the shaft 17. The outer end of each arm 20 is provided with a head 25 having an axial opening 26 receiving a crank pin 27, the pin 27 being held or secured in the opening 26 by means of a set screw 28. The outer end of each pin 27 projects outwardly beyond its arm 20 and extends through a roller bearing assembly 29 fitted in an opening provided therefor in the upper end of a link 30. A lubricating fitting 31 is provided for the bearing 20. The link 30 is held on the pin 27 and the bearing assembly 29 is retained in place by means of a washer 32 and pin 33. The lower end of each link 30 is provided with a lateral extending extremity or end portion 34 (see Figure 4) apertured to receive the upper end of a rod 35. Nuts 36 secure the rod 35 to the link 30 in various adjustments. Referring now to Figures 6, 7 and 8 it will be seen that the lower end portion of each rod 35 extends through the apertured body portion 37 of a lifting yoke 38, a head 39 at the lower end of each rod 35 engaging the body portion 37 of each lifting yoke to limit the relative upward movement of each rod 35 relative to its lifting yoke. Each lifting yoke 38 also includes a pair of diverging arms 40 integral with one side of its body portion 37 and offset from the body portion 37 as illustrated in Figures 7 and 8. The lower ends of the arms 40 are apertured to receive a pivot 41 (see Figure 6) which connects the lifting yokes to pivot lugs 42 integral with the saw frames 5. With this construction the offset arms 40 of the lifting yokes may be swung to a position shown in Figure 7 to provide the maximum spacing between the saws or they may be swung to the position shown in Figure 8 to provide minimum spacing between the saws. This operation of the lifting yokes together with the construction of the lifting units permits of either a one or two foot saw spacing. With separate lifting units this is not permissible as separate lifting units must be so spaced as to preclude a one foot spacing of the saws.

Returning now to the double lifting unit it will be seen that means is provided for selectively clutching or connecting either arm 20 to the shaft 17 for the purpose of either controlling the lowering movement of the arm and consequently of the associated saw frame or for the purpose of imparting a lifting movement to the arm and to its connected saw frame. In carrying out these purposes a toothed wheel 45 is provided on the shaft 17

adjacent each end thereof. The teeth of each wheel are designated at 45' and as shown in the drawings are uniform and are regularly spaced about the periphery of the wheel, each tooth having its opposed transverse or lateral faces substantially straight, whereby one transverse face of each tooth is adapted to coact with a lowering pawl, and the opposite transverse face of each tooth is adapted to coact with a lifting pawl. Each toothed wheel 45 has an inwardly offset hub 46 positioned on the shaft just inwardly of the hub of the adjacent arm 20 and keyed as at 47 to the shaft 17 (see Figure 4). The head 25 of each arm 20 overlies its associated toothed wheel 45 and is enlarged in a direction circumferentially thereof. The extremities of each enlarged head 25 are bifurcated and receive and pivotally support a pawl 49 cooperable with the toothed wheel 45 to control lowering of the arm 20 and saw frame 5 and also a pawl 50 cooperable with the toothed wheel 45 to impart lifting movement to the arm 20 and to the saw frame 5 connected thereto.

The lowering pawls at the two ends of the unit are of similar construction though of opposite hand, as shown in Figures 1 and 3. The lowering pawl 49 has a tail 51 which coacts with a substantially semi-annular track 52 to control its engagement with the toothed wheel 45, that is, to hold the pawl 49 out of engagement with the toothed wheel during the raising movement of the arm 20 and in the upper inactive or stopped position of the arm 20, wherein the arm 20 is just past upper dead center, as shown in Figure 2. During the lowering movement of each arm 20, the tail 51 of its pawl 49 leaves the track 52 so that the pawl 49 is engaged with the toothed wheel under the influence of its biasing spring 53. Each spring 53 is carried by and abutted against pins 53^a and 53^b provided therefor on its head 25 and has a button or bearing disc 53^c secured to its looped or bight portion and engaged with its pawl 49 to tend to urge it toward the wheel 45.

As shown in the drawings, each track 52 has its lower end secured to an outward extension 55 of a bracket 56 and its upper end to an angular lug 57 bolted as at 58 to this same bracket 56. One bracket 56 is shown in detail in Figure 5 and each bracket 56 is bolted as at 57 to lugs or attachment fixtures 59 formed integral with the base plate 12 (compare Figures 1, 2 and 3).

Each lifting pawl 50 is provided with a laterally extending lug 60 cooperable with a track-way 61, the major portion of which is formed integral with and projects outwardly from the bracket 56, but a shiftable section 62 of which, is slidably supported on the bracket 56 so that it may be aligned with the major portion of the track 61 or withdrawn inwardly from the plane of such major

portion for a purpose which will hereinafter more clearly appear. During the lowering movement of any arm 20 and of the saw frame connected thereto, its lifting pawl 50 is held 5 away from the toothed wheel by virtue of the engagement of its lug 60 of the pawl with the associated track 61. When the downwardly moving saw frame has reached its lowermost position the associated lug 60 is still engaged 10 with the shiftable section 62 of its cam track 61. The saw frame and arm 20 remain in this lowermost position under the influence of gravity.

It is to be noted that the lowering pawl 49 15 is not effective to impart lifting movement to the arm 20 or saw frame, and in the lowermost position of the arm 20, the teeth of the wheel 45 would only click idly past the lowering pawl 49 if the latter were left engaged with 20 the wheel. To eliminate this clicking, however, each pawl 46 is retracted in the lowermost position of the arm 20 since at such time its tail 51 engages the lower end of the track 52 to move the pawl 51 away from the toothed 25 wheel notwithstanding the action of its spring.

To permit the lifting pawl 50 of the lowered arm 20 to engage the toothed wheel and operate to elevate its arm 20 and the saw frame 30 connected thereto, the shiftable cam track section 62 of the unit is pulled inwardly and disengaged from the lug 60 of the pawl 50 thereby permitting the pawl 50 to engage the toothed wheel 45 and effect elevation of the 35 arm 20 and the saw frame. The engagement of this pawl 50 with the toothed wheel 45 continues until the arm 20 has just slightly passed beyond the upper dead center position when the lug 60 rides onto the upper end of the fixed 40 section 61 of the cam track to disengage the pawl 50 from the toothed wheel. At this time the rearward end of the pin 27 which projects inwardly beyond the head 25 of the arm engages a stop bolt 70 to bring the lifting mechanism to rest. Each bolt 70 is slidably fitted 45 in a guide-way 71 provided therefor on the bracket 56 and is interconnected with the shiftable track section 62 of its unit by means of a lever 72 fulcrumed as at 72' on the bracket 50 55 and having its ends appropriately connected with the bolt and with the slideable mounting member 62' of the shiftable track section. By virtue of this interconnection, when either bolt 70 is retracted the track section 62 interconnected thereto is projected into operative position, that is, into a position in which it will hold the lifting pawl retracted or inactive whereas when the bolt 70 is projected to operative position in which it 60 is effective to stop the arm 20 in elevated position, the associated track section 62 is retracted to permit the lifting pawl 50 of the unit to engage the toothed wheel and elevate the arm 20 and the saw frame.

65 Each bolt 70 has a pair of upstanding lugs

75 for receiving between them an arm 76 of a control lever designated generally at 77. The arm 76 of the control lever 77 has a downwardly extending pin 78 fitted in a bearing opening provided therefor on the bracket 56 and providing the support for the lever. Adjacent the pin 78 the arm 76 has a serrated hub 79 surrounding an upstanding threaded stud 80 integral with the arm 76 and adapted to be interfitted with an apertured and serrated hub 81 formed on a second lever arm 82 (compare Figures 2 and 3). The serrations of the hubs and two arms are interfitting in various adjustments and are held in engagement by a nut 83 threaded on the stud 80 and bearing against the hub 81. The arms 84 are offset from each other so that they may overlie with one another in the assembly without interference, as shown in Figure 3. The control lines are connected to the arms 84. Preferably, the bolts 70 are urged or biased to a projected position by means of coil springs 85 connected to the arm 76 of the levers and to anchoring lugs 86 on any suitable stationary part.

When any saw frame is elevated its arm 20 is in a position slightly beyond the upper dead center as shown in Figure 2 in which position the weight of the parts tends to lower the arm 20 and consequently to hold the rearward end of its pin 27 engaged with the associated stop bolt 70 which is projected at this time. If it is desired to lower any one of the elevated saw frames the appropriate control line is manipulated to retract the bolt 70 of the controlling unit of the selected saw frame. This simultaneously projects the shiftable cam track section 62 of the unit. As soon as the bolt 70 is withdrawn the weight of the parts starts the arm 20 to move in a clockwise direction as viewed in Figure 2. At the start of this movement, the tail of the lower pawl 49 rides off of the cam track 52 so that the lowering pawl snaps into engagement with the toothed wheel 45 to control the lowering of the saw frame. When the saw frame has been completely lowered the parts remain in lowermost position under the action of gravity since the shiftable cam track section 62 is projected at this time to hold the lifting pawl 50 disengaged from the toothed wheel. When the control line is again manipulated to cause or permit the bolt 70 to be projected, then the shiftable cam track section 62 is withdrawn from engagement with the lug of the pawl 50 and the pawl 50 snaps into engagement with the toothed wheel and effects lifting of the saw frame. The lifting movement is automatically stopped when the arm 20 reaches the position shown in Figure 2, due to the automatic disengagement of the pawl 50 from the wheel 45 and to the engagement of the rearward end of the pin 27 with the stop bolt 70.

With the construction above described, two

lifting units are served by the same counter shaft and a single gear and pinion. Further, the number of bearings required for two lifting units is materially reduced and the construction is rendered so compact as to permit of the provision of shiftable lifting yokes such as 40 whereby the saw spacing may be varied and the saws may be brought very close together.

10 The invention claimed is:

1. In a lumber trimmer having the usual saw frames, a double lift unit including a single counter shaft, two lifting arms, one at each end of the counter shaft, means co-operable with an intermediate portion of the counter shaft to rotate the same, means for controlling the connection of each lifting arm with the counter shaft, and connections between each lifting arm and a saw frame.
- 15 2. In a lumber trimmer having the usual saw frames, a double lift unit including a single counter shaft, two lifting arms, one at each end of the counter shaft, means co-operable with an intermediate portion of the counter shaft to rotate the same, means for controlling the connection of each lifting arm with the counter shaft, and connections between each lifting arm and a saw frame, each of said connections including a shiftable lifting yoke, said lifting yokes providing for variable spacing of the saws.

3. In a lumber trimmer having the usual saw frames, a double lift unit including a single counter shaft, two lifting arms, one at each end of the counter shaft, means co-operable with an intermediate portion of the counter shaft to rotate the same, means for controlling the connection of each lifting arm with the counter shaft, and connections between each lifting arm and a saw frame, each of said connections including a shiftable lifting yoke having offset arms positionable to vary the spacing of the saws.

4. In a lumber trimmer having the usual saw frames, a double lift unit including a constantly driven shaft, two lifting arms loosely mounted thereon, a toothed wheel fixed to the shaft adjacent each lifting arm, a lifting and a lowering pawl mounted on each arm and cooperable with the associated wheels, means controlling the action of said pawls and a connection between each arm and a saw frame.

5. In a lumber trimmer having the usual saw frames, a double lift unit including a constantly driven shaft, two lifting arms loosely mounted thereon, a toothed wheel fixed to the shaft adjacent each lifting arm, a lifting and a lowering pawl mounted on each arm and cooperable with the associated wheels, means controlling the action of said pawls and a connection between each arm and a saw frame, each of said connections including a shiftable lifting yoke positionable to vary the spacing of the saw frames.

6. In a lumber trimmer having the usual saw frames, a double lift unit including a constantly driven shaft, two lifting arms loosely mounted thereon, means for selectively clutching either arm to the shaft to control the lowering thereof or to impart lifting movement thereto, and a connection between each arm and a saw frame.

7. In a lumber trimmer having the usual saw frames, a double lift unit including a constantly driven shaft, two lifting arms loosely mounted thereon, means for selectively clutching either arm to the shaft to control the lowering thereof or to impart lifting movement thereto, and a connection between each arm and a saw frame, each of said connections including a shiftable lifting yoke positionable to vary the spacing of the saw frames.

8. In a lumber trimmer having the usual saw frames, a mechanical lift unit for imparting raising and lowering movement to a saw frame, and a connection between said lift unit and a saw frame and comprising a lift rod, a lifting yoke rotatably connected to said lift rod and having an offset arm, and releasable means for securing said arm to the saw frame in either of the positions to which it is shiftable.

In witness whereof, I hereto affix my signature.
